DESIGN FOR A BAKING PAN

Hugh McKay, Miami, Fla.

Application March 17, 1938, Serial No. 75,904

Term of patent 7 years

To all whom it may concern:

Be it known that I, Hugh McKay, a citizen of the United States, residing at Miami, in the county of Dade and State of Florida, have invented a new, original, and ornamental Design for a Baking Pan, of which the following is a specification, reference being had to the accompanying drawing, forming part thereof.

Fig. 2 is an underside view thereof, and Fig. 3 is an edge view of the pan.

I claim:

The ornamental design for a baking pan, as shown.

HUGH MCKAY.
